UNITED STATES PATENT OFFICE

146,939

DESIGN FOR A SERVICE STATION WRITE-UP DESK OR SIMILAR ARTICLE

Erling G. Fossum and Francis Lawrence Ayres,
Chicago, Ill., assignors to Stewart-Warner Corporation,
Chicago, Ill., a corporation of Virginia

Application March 2, 1946, Serial No. 127,041

Term of patent 14 years

(Cl. D33—7)

To all whom it may concern:

Be it known that we, Erling G. Fossum and Francis Lawrence Ayres, citizens of the United States, residing at Chicago, in the county of Cook and State of Illinois, have invented a new, original, and ornamental Design for a Service Station Write-Up Desk or Similar Article, of which the following is a specification, reference being had to the accompanying drawing, forming part thereof.

The drawing is a perspective view of a write-up desk, showing our new design.

The back of the desk is plain, and the right side is similar to the left side.

We claim:

The ornamental design for a service station write-up desk or similar article, substantially as shown, and described.

ERLING G. FOSSUM.

FRANCIS LAWRENCE AYRES.
